Mr. L. Sanderson and N. G. Neder ~~App're~~ to
Sanderson, Wolfe and Warren. of Troy, N. Y.
Letters Patent N°. 791, Dated May, 13th 1856.

The schedule referred to in these Letters Patent, and
making part of the same.

To all whom it may concern:

Be it known that we, Mr. L. Sanderson,
and N. G. Neder of Troy, in the County of Rensselaer, and State
of New York, have invented or produced a new and original
design for the side and front plates of a Cook Stove, which we
call the "Enterprise"; And we do hereby declare that the following
is a full, and exact description of the same, reference being had
to the annexed drawings, making a part of this specification;
in which,

Figure 1, is an elevation of a side plate.

Figure 2, an elevation of the front plates.

Figure 3, a section through 2, 2', in figure 1;

Figure 4, a section through 4, 4', in figure 1;

Figure 5, a section through 5, 5', in figure 2;

And Figure 6, a section through w, w', in figure 2;

The same letters refer to like parts in all the figures.

A, is the side plate. C, is the lower plate of the
front. B, is the upper front plate, having the two similar doors.
G, G. E, is the fire door, D, is the large, and F, the small door of the
oven. — The ornamental design of Cook-Stove plates, consists
in the arrangement of the canted stone work compositions a, a,
a, a, a, a, a, along the vertical corners of the plates; the pendant
gothic mouldings b, b, b, b, with their leaf ornaments f, f, f, f, and
alternating with the sunk trifid, gothic panels, e, e, e, e, — along
the upper portion of the side plate; the surrounding concave molding
